US0D1019543S

(12) **United States Design Patent** (10) **Patent No.:** **US D1,019,543 S**
(45) **Date of Patent:** **** Mar. 26, 2024**

(54) **POWER TOOL BATTERY**

(71) Applicant: **Dongguan Zheshi Electronic Technology Co., Ltd.**, Dongguan (CN)

(72) Inventor: **Lei Wang**, Zhumadian (CN)

(73) Assignee: **Dongguan Zheshi Electronic Technology Co., Ltd.**

(**) Term: **15 Years**

(21) Appl. No.: **29/906,560**

(22) Filed: **Nov. 7, 2023**

(51) LOC (14) Cl. **13-02**

(52) U.S. Cl.

USPC **D13/103**

(58) **Field of Classification Search**

USPC D13/102-106, 110, 118, 119, 184, 199;

D14/253, 432, 434

CPC H01M 6/00; H01M 6/14; H01M 6/10;

H01M 10/52

CLAIM

The ornamental design for a power tool battery, as shown and described.

DESCRIPTION

FIG. 1 is a rear, bottom, and left side perspective view of a power tool battery showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

Broken lines in the drawings depict portions of the power tool battery that form no part of the claimed design.

1 Claim, 7 Drawing Sheets
